CLAIM

We claim the ornamental design for engine cylinder, as shown and described.

DESCRIPTION

FIG. 1 is a perspective view of an engine cylinder; FIG. 2 is a rear view of the engine cylinder of FIG. 1; FIG. 3 is a front view of the engine cylinder of FIG. 1; FIG. 4 is a right side view of the engine cylinder of FIG. 1; FIG. 5 is a left side view of the engine cylinder of FIG. 1; FIG. 6 is a bottom view of the engine cylinder of FIG. 1; and,

FIG. 7 is a top view of the engine cylinder of FIG. 1. The broken line showing of the environment is for illustrative purposes only and forms no part of the claimed design.
